UNITED STATES PATENT OFFICE.

JOHN C. WOODY, OF MOUNT VERNON, INDIANA, WILLIAM R. DANLEY, OF DENVER, AND WILLIAM H. YOUNG, OF ROCKYFORD, COLORADO.

DRIVING-GEAR.

SPECIFICATION forming part of Letters Patent No. 696,782, dated April 1, 1902.

Application filed July 10, 1901. Serial No. 67,708. (No model.

To all whom it may concern:

Be it known that we, JOHN C. WOODY, of Mount Vernon, in the county of Posey and State of Indiana, and WILLIAM R. DANLEY, of Denver, in the county of Arapahoe, and WILLIAM H. YOUNG, of Rockyford, in the county of Otero, State of Colorado, citizens of the United States, have invented new and useful Improvements in Driving-Gears, of which the following is a full, clear, and exact description.

The invention relates to treadle-power for actuating small machines, such as sewing-machines, coffee-mills, and the like. The object of the invention is to provide a new and improved driving-gear which is simple and durable in construction, very effective in operation, and arranged to directly actuate the machine to be driven and to support the same on the main frame.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a plan view of the same. Fig. 3 is a rear end elevation of the same. Fig. 4 is a detail section on the line 4-4 of Fig. 1, and Fig. 5 is a detail section on the line 5-5 of Fig. 1.

The improved driving-gear is mounted on a frame consisting, essentially, of spaced longitudinally-extending bars A A, connected at their forward ends with a platform B, having legs C, and the rear ends of the said bars A are secured to a standard D, resting at its lower end on the floor the same as the legs C, to hold the bars A A and the platform B approximately in a horizontal position.

On the platform B is bolted or otherwise secured a bearing E for carrying a machine F to be driven, and the upper portion of the said bearing E is connected by a brace G with the upper end of the standard D, the brace G being preferably made of telescopic sections G' and G'', fastened together by suitable set-

screws G³. A center brace H also extends from the upper end of the standard D to the bars A to meet the latter at or near the middle thereof, and adjustable legs I are secured to the bars A directly below the connection of the center brace H with the said bars. 55

On the bars A between the legs I and the standard D is mounted to slide longitudinally a bearing J, in which is journaled a crank-shaft K, carrying crank-arms K', supporting pedals K², adapted to be engaged by the feet of the operator seated on a seat L, having its seat-post L' vertically adjustable in the upper end of the standard D, the post L' being secured in place after the desired adjustment is made by a set-screw L².

The operator seated on the seat L takes hold of a handle-bar N, longitudinally adjustable on the upper part G' of the brace G. On the crank-shaft K centrally between the bearings is fastened a sprocket-wheel O, connected by a sprocket-chain O' with a sprocket-wheel O², secured on the main shaft F' of the machine F to be driven, the said shaft being journaled in the bearing E and provided at its end with suitable fly-wheels F². Now in order to give the desired tension to the chain O the bearing J is made adjustable, and for this purpose a screw-rod J' and nut J² are provided 75 to adjust the bearing J longitudinally on the bars A.

By connecting the several parts of the frame with each other, as described, a very rigid and durable frame is secured, and by having 85 the upper brace G adjustable proper adjustment can be made between the standard D and the bearing E. This arrangement of the brace G is of great utility, as it allows for adjustment to suit the machine to be operated and permits of securely bracing the machine against strain from the chain, thus taking all strain from the fastening devices that secure the machine to the platform and preventing jarring. 90

Having thus described our invention, we claim as new and desire to secure by Letters Patent—

1. A driving-gear, comprising a frame arranged to support the machine to be driven, a crank-shaft having crank-arms provided with pedals, bearings for the crank-shaft ad-

justable on the frame, a sprocket-chain and sprocket-wheel connection between the crank-shaft and the main shaft of the machine to be driven, the sprocket-wheel being arranged 5 centrally between the bearings, a seat on the said frame, a brace connected with the frame below the seat and adapted to engage the machine to be driven, the brace being adjustable in length to suit the machine to be operated, 10 and to brace the same against strain from the chain, and a handle-bar on the said adjustable brace, as set forth.

2. A driving-gear, comprising a frame having longitudinal spaced bars, a platform at 15 the front end of the bars for supporting the machine to be driven, a crank-shaft having crank-arms provided with pedals, a sprocket-chain and sprocket-wheel connection between the said crank-shaft and the main shaft of 20 the machine to be driven, a standard at the rear end of the bars, a seat carried by the said standard, a handle-bar on the frame, the bearings of the crank-shaft being mounted to slide longitudinally on the spaced bars in 25 front of the standard, and means for adjusting the bearings, as set forth.

3. A frame for a driving-gear, comprising longitudinal spaced bars, a platform on the front end of the bars, legs for supporting the 30 front ends of the bars and platform, a standard at the rear ends of the bars, bearings on the said platform for supporting the machine to be driven, an upper brace connecting the bearings with the standard, the said upper 35 brace being adjustable in length to compensate for changes in the position of the bearings and a center brace connecting the standard with the said bars, as set forth.

4. A frame for a driving-gear, comprising longitudinal spaced bars, a platform on the 40 front end of the bars, legs for supporting the front ends of the bars and platform, a standard at the rear end of the bars, a bearing adapted to be secured on the said platform for supporting the machine to be driven, an 45 upper brace adapted to connect the standard with the said bearing, the brace being made in sections and adjustable to suit the position of the machine to be operated, a center brace connecting the standard with the said 50 bars, and a set of adjustable legs on the said bars below the point of connection of the center brace with said bars, as set forth.

5. A frame for a driving-gear, comprising longitudinal spaced bars, a platform on the 55 front ends of the bars, legs for supporting the front ends of the bars and the platform, a standard at the rear ends of the bars, bearings on the said platform for supporting the machine to be driven, an upper brace connecting the bearings with the standard, the 60 brace being made in telescopic sections fastened together whereby it may be adjusted to suit changes in the position of the bearings on the platform, and a center brace connecting the standard with the said bars. 65

In testimony whereof we have signed our names to this specification in the presence of two subscribing witnesses.
